UNITED STATES PATENT OFFICE.

VERNON ROYLE, OF PATERSON, NEW JERSEY.

ROUTING-MACHINE.

No. 893,940.

Specification of Letters Patent.

Patented July 21, 1908.

Application filed January 21, 1905. Serial No. 242,191.

To all whom it may concern:

Be it known that I, VERNON ROYLE, a citizen of the United States, and resident of Paterson, in the county of Passaic and State 5 of New Jersey, have invented a new and useful Routing-Machine, of which the following is a specification.

My invention relates to routing machines and more particularly to a routing machine 10 in which cylinders of different sizes, as well as a flat table, may be brought into position to support the plate during the operation of the routing tool on it.

A practical embodiment of my invention 15 is represented in the accompanying drawings, in which

Figure 1 is a view in front elevation of so much of the routing machine as is necessary to illustrate my invention; Fig. 2 is a view of 20 the same in end elevation; Fig. 3 is a longitudinal section in the plane of the line A—A of Fig. 2; Fig. 4 is a top plan view of the flat table for supporting the plate; Fig. 5 is a section in detail of the clamp for engaging 25 one edge of the plate when resting on the flat table, and Fig. 6 is a section in detail of the clamp for engaging the opposite edge of the plate.

My present invention provides for mounting 30 a plurality of cylinders, in the present instance two, and a flat table on a common support and so arranged that either one of the cylinders or the table may be swung into position with respect to the cutting tool 35 without requiring the interchange of cylinders as has heretofore been common.

The upright pillar which forms the main support for the operating parts of the router is denoted by 1 and is provided with a head 40 piece 2 on which the cutter supporting mechanism is mounted.

On the side of the pillar 1 there is a track 3 along which a cylinder supporting slide 4 may be moved vertically to bring the cylinder 45 into proper position to adjust the cylinder in the proper relation to the cutter.

The slide 4 and parts carried thereby are adjusted vertically by means of a screw 5 which passes downwardly through a bracket 50 6 on the pillar, a nut 7 being engaged with the screw 5 and having its periphery developed into bevel gear 8 which registers with a bevel gear 9 on a shaft 10 provided with a hand wheel 11. The combined wheel 55 and nut 7 and 8 rests with its face on top of

the bracket 6 and by the engagement of the nut with the screw 5 supports the slide 4 and its parts. The weight of the slide 4 and the parts carried thereby is such that they will feed downwardly under the influence of 60 gravity alone when the nut 7 is turned in a direction to permit them to do so.

From the slide 4 there projects a taper axle 12 and on this axle a sleeve 13 bears at its inner and outer ends. The sleeve 13 is provided with cylinder and table supporting arms which radiate therefrom as follows:— The arms 14 and 15 (see Fig. 1) which support, respectively, one end of each of two cylinders as well as a pair of bifurcated arms 16 (see Fig. 2) for supporting a flat table are preferably formed integral with the sleeve 13 while the arms 17 and 18 which support the opposite ends of the cylinders are conveniently formed integral with a hub 19 which is 70 keyed onto the end of the sleeve 13 and rotates together with the sleeve. The cylinder carried by the arms 14 and 17 is denoted by 20 and the cylinder carried by the arms 15 and 18 is denoted by 21. The cylinder 20 is 75 of less diameter than the cylinder 21 for the purpose of supporting a plate having a curve of lesser radius.

A hollow trunnion 22 at one end of the cylinder 20 is received in a suitable bearing in 85 the arm 14 and a hollow trunnion 23 at the opposite end of the cylinder 20 is received in a bushing 24 projecting from a plate 25 supported on the end of the sleeve 13 in proximity to the arms 17 and 18. The bushing 24 90 projects from the plate 25 inwardly and is received within a suitable bearing in the arm 17. In like manner the cylinder 21 is provided with a hollow trunnion 26 at one end which is received in a suitable bearing in the 95 arm 15 and the opposite end of the said cylinder is provided with a hollow trunnion 27 which is received in a bushing 28 projecting from the plate 25 into a suitable bearing in the arm 18. The trunnion 23 on the cylinder 20 has a gear wheel 29 secured to its outer end and the trunnion 27 of the cylinder 21 has a gear wheel 30 secured to its outer end. 100

Because of the greater diameter of the cylinder 21, its longitudinal axis is located 105 further from the central axis of the axle 12 in order to leave room between its surface and the sleeve 13 for the clamping rings 31 and 32 which hold the plate in position on the cylinder. On this account, the gear wheel 30 on 110

the trunnion 27 of the larger cylinder is of greater diameter than the gear wheel 29 on the trunnion 23 of the smaller cylinder, the relation being such that when the cylinder 21 is swung on the axle 12 into operative position with respect to the cutter, the lowermost point on the wheel 30 will occupy the same position as that which the lowermost point on the wheel 29 occupied when the cylinder 20 was in operative position thereby making it feasible to utilize a single driving pinion 33 for rotating the cylinders of different diameters while in operative position under the cutter.

15 The driving pinion 33 is fixed on a short shaft 34 mounted in a bearing 35 formed in a cap plate 36 fixed on the outer end of the axle 12. The shaft 34 is provided with a hand wheel 37 for operating it. The plate 36 is centered and locked in position by means of a bolt 38 passing through it and screwed into the end of the axle 12 and a dowel 39 set in the end of the axle 12 to one side of the center enters a socket in the plate 36 when the latter is in the proper relation to the axle and serves to prevent any rotary movement of the plate 36 with respect to the axle 12.

The plate 36 carries a spring actuated dog 40 which enters one or another of the sockets 41 in the end of the sleeve 13 to lock the latter in the proper rotary adjustment on the axle 12 to bring either the cylinder 20, the cylinder 21 or the table carried by the arm 16, into operative position below the cutter. The plate 36 also has attached thereto arms 42 and 43 (see Fig. 2) on the ends of which are partial hoods 44 and 45, respectively, which hoods combine with caps 46 and 47 carried by the plate 25 to house the gear wheels 29 and 30, when the said wheels, together with their respective cylinders, are rocked out of operative position with respect to the cutter.

The outer surfaces of the cylinders 20 and 21 are screw threaded for receiving the plate holding rings, those hereinbefore referred to and denoted by 31 and 32, being made to register with the screw threaded surface of the cylinder 21, and those denoted by 48 and 49 being constructed to register with the screw threaded surface of the cylinder 20, a plate held by these rings being indicated by 50, Fig. 3.

The flat table held by the pair of bifurcated arms 16 is denoted by 51. It is secured at its opposite ends to the branches of the arms, as shown at one corner, Fig. 2, by the bolts 52, 53, which pass through a depending portion of the table into a branch of one of the arms 16 it being understood that a similar fastening is repeated at each of the four corners of the table. The table 51 is provided with suitable clamps 54 and 55 for locking the plate to its face.

The clamp 54 is placed in the position desired and locked by means of the wheel 56 in

a manner well known in the art while the clamp 55 is adjusted by engaging it with some one of the holes 57 in proximity to the edge of the plate and is then forced into contact with the plate by being slid along the surface of the table by means of the lever 58.

In rocking the table 51 into position beneath the cutter if its advance corner should be so high as to interfere with the cutter the entire cylinder and table supporting frame 75 may be lowered by operating the screw 5 heretofore referred to and when the table is in register, it may be again bodily lifted to bring the plate into position to be operated upon by the cutter.

80 The structure hereinabove described admits of moving the cylinders of varying diameters into position by a simple swinging of their supporting frame and provides at the same time for operating upon flat plates thus 85 making the machine quite universal in character and saving a great amount of time and labor which has heretofore been commonly expended in removing a cylinder and placing another in position.

90 What I claim is:—

1. The combination with a cutter, of a plurality of horizontally arranged cylinders of different sizes for supporting on their curved faces plates to be cut and means 95 whereby one or another of the cylinders may be moved at pleasure into operative relation to the cutter with its curved face opposed to the cutter.

2. The combination with a cutter, of a 100 work supporting cylinder and a work supporting table, a frame common to the said work supports and means for moving the frame to bring the cylinder or table into operative relation to the cutter at pleasure.

105 3. The combination with a cutter, of a plurality of work supporting cylinders of different sizes, a moving support for bringing one or another of the cylinders into operative relation to the cutter and gear for rotating 110 the cylinders when in such operative relation.

4. The combination with a cutter, of a plurality of work supporting cylinders of different sizes provided with operating gears, 115 a driving pinion for rotating the cylinders and means for moving the several cylinders one at a time into operative position with their gears in engagement with the driving pinion.

120 5. The combination with a cutter, of a sleeve mounted in rotary adjustment on an axle, work supporting cylinders of different sizes carried by the sleeve, a cylinder driving pinion supported by the axle, gears carried 125 by the cylinders in position to be engaged with the said pinion and means for locking the sleeve in different rotary adjustments.

6. The combination with a cutter, of a plurality of work supporting cylinders, 130

means for moving the cylinders in circular paths into and out of operative relation to the cutter and means for moving the cylinders bodily in a right line toward and away from the cutter.

7. The combination with a cutter, of a plurality of work supporting cylinders, means for moving the cylinders in circular paths into operative relation to the cutter, means for 10 rotating a cylinder on its axis when in operative position and means for reciprocating the

cylinders bodily in a right line toward and away from the cutter.

In testimony, that I claim the foregoing as my invention, I have signed my name in 15 presence of two witnesses, this 13th day of January 1905.

VERNON ROYLE.
